UNITED STATES PATENT OFFICE.

BENJAMIN P. COBB, OF ODESSA, MISSOURI.

CHICKEN-COOP.

SPECIFICATION forming part of Letters Patent No. 372,966, dated November 8, 1887.

Application filed July 30, 1887. Serial No. 245,691. (No model.)

To all whom it may concern:

Be it known that I, BENJAMIN P. COBB, a citizen of the United States, and a resident of Odessa, in the county of Lafayette and State 5 of Missouri, have invented certain new and useful Improvements in Chicken-Coops; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my improved chicken-coop. Fig. 2 is a longitudinal vertical sectional view. Fig. 3 shows the coop in its folded position, and Figs. 4 and 5 are detail views.

Similar letters of reference indicate corresponding parts in all the figures.

My invention has relation to folding chicken-coops; and it consists in the improved construction and combination of parts of the same, as hereinafter more fully described and 25 claimed.

In the accompanying drawings, the letter A indicates the bottom or base of my improved coop, having buckles B B suitably secured to the bottom thereof by loops b.

30 The sides C C of the coop are provided with uprights D, journaled within bearings E, secured to the bottom of the coop. The lower slats or wires, F, of the side pieces pass through perforations in said bearings and uprights, 35 thereby forming a complete hinge, upon which the sides may turn.

To the top rails of the sides C are secured springs G, of steel or other suitable material, said springs being of angular shape, the laterally-extending portions thereof overlapping the side rails of the removable top or cover H and serving to retain said cover securely in 40 position.

The cover H is provided with the ordinary 45 opening, I, through which the fowls may be placed within or removed from the coop, and is also provided on each end with straps J J.

K K represent the hinged ends of the coop, having bails L L, through which the straps J 50 J pass, and which straps are secured to the

buckles B B, thereby retaining the end pieces securely in position.

The operation of my improved device is as follows: When the coop is in its folded position, (shown in Fig. 3,) the straps are first released from the buckles and the top withdrawn. The hinged side is now raised and the top or cover placed under the springs G. The opposite side is next raised, the spring attached thereto likewise engaging the top or cover. 60 After this the hinged end pieces are properly adjusted and the straps passed through the bails and secured to the buckles. After the chickens have been removed from the coop and it is ready for return to the shipper or sender, 65 the straps are unbuckled, the ends or sides pushed in, and the top permitted to fall. The coop may now be strapped together in its folded position and compactly secured with but a minimum of labor being necessary. 70

It will be seen that when the crate is knocked down the side pieces will lie perfectly level and horizontal upon the end pieces, K, said side pieces being pivoted sufficiently high to readily permit of this arrangement, thereby 75 forming a convenient and compact package for transportation or shipment.

From the foregoing description, taken in connection with the accompanying drawings, the operation and construction of my improved 80 device will be readily understood without requiring further explanation.

Having thus described my invention, I claim and desire to secure by Letters Patent of the United States—

85 The combination of the bottom or base piece having buckles at opposite ends, the hinged end pieces provided with bails, the hinged side pieces, and the removable top or cover provided with straps at each end thereof 90 adapted to be inserted through the bails and fastened to the buckles.

In testimony that I claim the foregoing as my own I have hereunto affixed my signature in presence of two witnesses.

BENJAMIN P. COBB.
